UNITED STATES PATENT OFFICE.

GEORGE W. FURTH, OF CLEVELAND, OHIO.

TIE-HANDLE.

1,141,790.

Specification of Letters Patent. Patented June 1, 1915.

Application filed April 10, 1913. Serial No. 760,312.

To all whom it may concern:

Be it known that I, GEORGE W. FURTH, a citizen of the United States, residing at Cleveland, in the county of Cuyahoga and 5 State of Ohio, have invented a new and useful Tie-Handle, of which the following is a specification.

The device forming the subject matter of 10 this application is a handle, adapted to receive a strip of flexible material, such as a wire, to facilitate the tightening of the strip about a bale or like object.

One object of the present invention is to 15 provide means whereby the insertion of the strip into the handle is facilitated.

Another object of the invention is to provide novel means for mounting the gripping members and for holding the same in place.

Another object of the invention is to provide 20 novel means whereby the strip-guiding tube is directed to place and is held in place.

The invention aims to provide a device 25 of the above mentioned type in which a proper adjustment of the strip receiving tube and the terminal ferrule may be accomplished.

It is within the scope of the invention to 30 improve generally and to enhance the utility of, devices of that type to which the present invention appertains.

With the above and other objects in view, which will appear as the description proceeds, the invention resides in the combination and arrangement of parts and in the 35 details of construction hereinafter described and claimed, it being understood that changes in the precise embodiment of invention herein disclosed can be made within the scope of what is claimed without departing 40 from the spirit of the invention.

In the drawings:—Figure 1 shows the invention in longitudinal section; Fig. 2 is a longitudinal section, the cutting plane being passed at right angles to the cutting plane 45 in Fig. 1, parts appearing in elevation; Fig. 3 is a transverse section on the line 3—3 of Fig. 2; Fig. 4 is a transverse section on the line 4—4 of Fig. 2; Fig. 5 is a fragmental side elevation.

50 In carrying out the invention there is provided a body 1 which is a composite structure, the body 1 including a handle 2 which may be fashioned from wood. The handle 2 is equipped with a longitudinal, 55 wire receiving bore 3, and at one end of the

handle 2 a recess 4 is formed, the recess, ordinarily being concentric with the bore 3.

Applied to the recessed end of the handle 2 is a support 5 which may be in the form of a disk provided with a reduced neck 6 which registers in the recess 4. The support 5 is provided with an opening 5^a concentric with the bore 3 of the handle 2. Projecting from the support 5 upon either side of the opening 5^a are ears 7.

The handle 2 is equipped, relatively near to its recessed, wider end, with a transverse opening 8 which extends entirely through the handle. Mounted in the opening 8 is an anchor 9 which may be a bar or block of metal, equal in length with the diameter of the handle 2 at the opening 8. Securing elements, which may be screws 10, pass through the support 5 and enter the handle 2. The screws 10 extend across the opening 8 and 70 pass through the anchor 9. Thus, the anchor 9 is prevented from moving longitudinally in the opening 8, and an aperture 11 which is formed in the anchor 9 is held in coaxial relation with respect to the bore 3. 75

The invention further includes a metal tube 12 which is mounted in the bore 3 of the handle 2. The tube 12 at one end is threaded or otherwise secured in the opening 5^a in the support 5. The tube 12 passes through the 80 opening 11 in the anchor 9 and thus the anchor constitutes a means for guiding the tube 12 into engagement with the opening 5^a in the support 5. That end of the tube 12 which is engaged with the support 5 is flared 90 in its bore, as shown at 14, so as to permit the wire to coöperate properly with the tube. The opposite end of the tube 12 protrudes beyond the end of the handle 2, as shown at 15. 95

Mounted upon the last specified end of the handle 2 and held in place by one or more tacks 18 or the like is a ferrule 16. The inner end of the ferrule 16 abuts against a shoulder 17 which may be formed in the 100 handle 2. In the outer end wall of the ferrule 16 there is an opening 19, the outer extremity of which is outwardly flared as indicated at 20, to facilitate the outward passage of the wire, the inner end of the opening 105 19 being inwardly flared, or otherwise enlarged in diameter as shown at 21. The enlarged portion 21 of the opening 19 receives the protruding end 15 of the tube 12, and thus when the wire passes out of the end of 110

the tube 12, the wire will be directed into the opening 19. Further, the enlarged portion 21 of the opening 19 which receives the protruding end 15 of the tube 12, permits a longitudinal adjustment of both the tube 12 and the ferrule 16 with respect to the handle 2. Thus, the ferrule 16 may be mounted readily on the handle 2 without adjusting to a nicety, the length of the protruding end 15 of the tube 12. Conversely, variations in the location of the shoulder 17 will not cause the ferrule 16 to abut against the protruding end 15 of the tube 12 and prevent the inner end of the ferrule 16 from coming 15 into abutment with the shoulder.

Extended through the ears 7 upon the support 5 are pins 22. The gripping means in the present instance comprises a pair of toothed cam levers 23 provided in their inner edges with open notches 24 which receive the pins 22, to provide for a swinging movement for the cam levers.

A housing 25 is provided, the same comprising a cap 26 which fits around the edge 25 of the support 5, and a collar 27 which surrounds the cap, the cap being peripherally recessed to receive the collar. The collar 27 is equipped in its edge with notches 28 registering with notches 29 in the edge of the 30 cap 26. The ends of the cam levers 23 pass outwardly through the registering notches 28 and 29. The housing 25, comprising the cap 26 and the collar 27 is held in place by securing elements, which may be screws 30 35 entering the edge of the support 5. If desired, the screws 30 may be long enough to bear upon the screws 10, the screws 30 thus constituting means for holding the screws 10 in place.

40 The invention further includes a plunger 32 which may comprise a disk located within the cap 26, the plunger including a neck 33 which is slidably received in an opening in the end wall of the cap 26. A compression spring 35 bears against the inner face of the end wall of the cap 26 and against the disk portion of the plunger 32. The outer portion of the bore of the neck 33 may be flared, as indicated at 34, to facilitate the insertion 50 of the wire 36.

Devices of this general type, hitherto, have proven but partially successful, by reason of the fact that the wire 36 not infrequently sticks in the bore of the handle 2, notably if the wire is slightly sinuous, or if the extremity of the wire is bent or barbed during the cutting of the wire. The metallic tube 12 serves to overcome this difficulty, and to render the sliding of the 60 wire 36 of the handle 2, a matter easy to be accomplished.

By pressing the exposed ends of the cam levers 23 toward the handle 2, the inner ends of the cam levers will be spaced laterally from the bore of the tube 12, so that

the wire 36 may be mounted in place as shown in Fig. 2, it being noted that the spring pressed plunger 32 bears against the cam levers 23 adjacent their inner ends. So soon, therefore, as the levers 23 are released, 70 the spring 35 will thrust the plunger 32 inwardly and cause the toothed inner ends of the cam levers 23 to grip the wire 36.

It is to be observed that the spring 35 and the plunger 32 exercise two functions. 75 First, as hereinbefore pointed out, they constitute means for actuating the cam levers 23, so that the same will engage with the wire; secondly, they serve to maintain the notches 24 in the cam levers 23 engaged 80 with the pins 22 which are carried by the support 5.

The cam levers 23 are subjected to considerable wear, and must be renewed at intervals. One object of the invention is to 85 facilitate the changing of the cam levers. It is to be noted that the cam supporting pins 22 lie relatively close to the free end of the collar 27, and as a consequence, the pins cannot be removed in practice, without re- 90 moving the collar. In the present instance, the cap 26, only, is removed, and thereupon, the pressure of the plunger 32 upon the cam levers 23 is relieved, it being possible to lift the cam levers free from the pins 22 without 95 removing the collar 27.

Referring to Fig. 4 it will be observed that the pins 22 are located in the ears 7 of the support 5. The cap 26 lies in the path of longitudinal movement of the pins 22, and before the pins 22 can move endwise out of the ears 7, the pins will strike the cap 26. The cap 26, therefore, constitutes means for retaining the pins in the support.

Having thus described the invention, what 105 is claimed is:

1. In a device of the class described, a handle having a bore and provided with a transverse opening extended therethrough from side to side and intersecting the bore; 110 an anchor mounted in the opening and extended across the bore, the anchor having an aperture; a support mounted on one end of the handle; a securing device engaged with the support and the anchor and passing through a portion of the handle, the securing device constituting means for alining the aperture in the anchor with the bore; a tube mounted in the bore and in the aperture and assembled with the support; and a 120 gripping means on the support and co-operating with the tube.

2. In a device of the class described, a handle having a bore; a support mounted on the handle and having a projection; a 125 cam lever having an open notch in one edge receiving the projection; and a single yieldable means engaging the cam to actuate the cam with respect to the bore and to hold the notch engaged with the projection. 130

3. In a device of the class described, a body, having a bore and comprising as constituent parts, a support and a cam, one of which constituent parts is provided with a notch in its edge, the other of which constituent parts is provided with a projection registering in the notch; and a single yieldable means engaging the cam to actuate the cam with respect to the bore and to hold the 10 projection and the notch interengaged.

4. In a device of the class described, a body provided with a bore and including a support; a cam coöperating with the bore;

and a cap assembled with the body and inclosing the support; the cam and the support having interengaged elements permitting a disengaging of the cam from the support when the cam and the cap are moved in a common direction.

In testimony that I claim the foregoing as 20 my own, I have hereto affixed my signature in the presence of two witnesses.

GEORGE W. FURTH.
